Inventor
SARAH E. CANTRALL
By Atty. N. Dubois.

UNITED STATES PATENT OFFICE.

SARAH E. CANTRALL, OF ATHENS, ILLINOIS.

COMBINED CUTTER AND BASTER.

No. 874,829.

Specification of Letters Patent.

Patented Dec. 24, 1907.

Application filed May 20, 1907. Serial No. 874,688.

To all whom it may concern:

Be it known that I, SARAH E. CANTRALL, a citizen of the United States, residing at Athens, in the county of Menard and State of Illinois, have invented a certain new and useful Combined Cutter and Baster, of which the following is such a full, clear, and exact description as will enable others skilled in the art to which it appertains to make and 10 use my said invention.

The purposes of this invention are to provide in connection with shears, sewing mechanism operative by the shears, to sew loosely together or baste the fabrics cut by the 15 shears; to provide stitch-forming mechanism of improved construction and to provide simple and effective means for connecting the sewing mechanism with the shears.

With these ends in view my invention consists in the novel features of construction and combinations of parts shown in the annexed drawings to which reference is hereby made and hereinafter particularly described and finally recited in the claim.

In the drawings similar reference letters and numerals designate like parts in the several views.

Figures 1, 2 and 3 are respectively a side elevation, a top plan and a bottom plan of the apparatus. Fig. 4 is an enlarged top view of the looper, showing the position of the looper jaws relative to the needle at the instant before the looper enters the loop. Fig. 5 is an enlarged top view of the looper showing the position of the jaws relative to the needle when the needle has moved part way downward between the jaws and the shoulders of the jaws have engaged the loop substantially as shown in Fig. 12, also showing 30 in dotted lines the position of the jaws relative to the needle at the instant preceding the withdrawal of the jaws from the needle; Fig. 6 is an enlarged side elevation of the looper; Fig. 7 is an enlarged partial vertical 35 section on the line 7-7 of Fig. 2 and shows the means for connecting the needle with one blade of the shears; Fig. 8 is a perspective view of the presser plate detached; Fig. 9 is a perspective view of the table detached and 40 Figs. 10 to 15 inclusive, are diagrams illustrating the forming of the loop and the stitch at different stages of the operation. In some of these views the table 3 and the presser plate 2 are shown as abnormally separated 45 from each other in order to more clearly illus-

trate the fabrics, and the thread situated between the plates.

The shear blades 1 and 1^a are of the usual form and are connected by a pivot 1^b. The blades 1 and 1^a are respectively provided with studs 1^c which may be integral with the blades or may be made separately and secured thereon by any suitable means.

The presser plate 2 is firmly secured on the blade 1^a and extends lengthwise parallel to the blade, the inner edge of the plate being away from the blade 1^a a distance sufficient to permit the cutting edge of the blade 1 to enter the space between the presser-plate 2 and the blade 1^a. The plate 2 has a laterally projecting lug 2^a, pierced by holes 2^b. Screws 2^c extend through the holes 2^b and screw into corresponding holes in the upper part of the blade 1^a, and secure the plate 2 on the blade 1^a. The presser plate bears upon the fabrics 75 on the table 3 when the shears are closed and serves to keep the fabrics smooth during the cutting and prevents tangling of the thread during the operation of basting.

A table 3 is firmly secured on the blade 1^a by screws 3^a extending through lugs 3^b on the table 3 and screwing into suitable holes in the blade 1 in such position that when the shears are closed the presser plate 2 will be 80 parallel to the table 3.

Toggle arms 4 are pivotally connected with the blades 1 and 1^a, respectively and with each other, and with the looper bar 5; in such manner that the opening and closing of the shears will impart a reciprocating 90 movement to the looper bar. The looper bar 5 slides freely in a stationary guide 5^a on the under side of the table 3. The looper plate 6 is secured on the bar 5.

A fixed jaw 7 is secured on the looper plate 6 by rivets 7^b or equivalent securing devices. A movable jaw 7^a is pivotally connected with the plate 6. The jaws 7 and 7^a have shoulders 7^c which prevent the thread from slipping too far rearward on the jaws while the 100 looper is moving forward during the making of the stitch.

A spring 8 is mounted on the plate 6 and the free end of the spring acts on a lug 7^d on the jaw 7^a to normally hold the point of the movable jaw 7^a in contact with the point of the fixed jaw 7; but yields to permit the jaw 7^a to move sufficiently for the needle 9 to pass between the jaws during the rearward movement of the looper.

A plate 10 secured in a horizontal position on the blade 1^a at right angles to the blade, serves as a spool support and a needle support. The spool 11 carrying the thread used in basting turns on a fixed vertical stem 10^a on the plate 10. The plate 10 has an integral circular, tapering and screw threaded split stud 10^b having a central opening 10^c in which the shank of the needle 9 fits. A nut 12 screws onto the stud 10^b and presses together the members of the stud to hold the needle firmly in any position in which it may be set. A channeled block 13 secured on the blade 1 serves to guide the needle. The opening of the shears during the operation of cutting causes the toggle arms 4 to move the looper forward into the position shown in Fig. 10 and also causes the needle to assume the raised position shown 20 in the same view.

During the operation of cutting the shears move forward on the fabric and the length of the stitch depends upon the extent of the forward movement of the shears at each step of 25 the cutting. Upon the partial closing of the shears the needle will descend, the position of the needle at different stages of its descent being shown in Figs. 11, 12 and 13. During the descent of the needle the point of the 30 needle passes downward between the jaws 7 and 7^a as shown in Figs. 5 and 12. During the latter part of the downward movement of the needle, incident to the closing of the shears, the toggle arms 4 act to move the looper 35 rearward, away from the needle, into the position shown in Fig. 13. The thread Y carried in the eye of the needle at this stage of the operation extends downward through the fabrics and lies alongside the needle as 40 shown in Fig. 13. Upon again opening the shears the needle will begin to rise and will cause the thread to loop as shown in Fig. 14

and further opening of the shears will cause the looper to move forward into the loop, between the needle and the thread, and the shoulders 7^b engaging with the thread will push the loop forward as indicated in Fig. 15, the position of the loop being such that when the needle next descends it will pass downward through the loop and between the jaws 50 7 and 7^a, thus forming one stitch; and this will be repeated and successive stitches will be formed, so long as the apparatus continues in operation.

In practice the fabrics X will be placed face to face and the shears will be operated to cut them to the desired pattern and the operating of the shears will cause the needle and looper to coöperate to baste the fabrics as already described.

Having fully described my invention, what I claim as new, and desire to secure by Letters Patent, is:

A combined cutter and baster comprising shear-members pivotally connected with each other and having studs, a needle mounted on one of the shear-members, a presser plate mounted on the same shear-member and adapted to permit the passage of the cutting edge of the complementary shear-member, a 60 table fixed on the complementary shear-member, a looper mounted on the complementary shear-member and adapted to coöperate with the needle, arms pivotally connected with each other and with the studs on the shear-members, and a rod connecting the looper with said arms.

In witness whereof I have hereunto signed my name, at Athens, Illinois, this 10th day of November 1906.

SARAH E. CANTRALL.
